CURTAIN ROD SUPPORTING BRACKET

Filed Dec. 26, 1929

Inventor:

James H. Boye,
By Fisher, Clapp, Soans + Pond, Atty.

UNITED STATES PATENT OFFICE

JAMES H. BOYE, OF CHICAGO, ILLINOIS, ASSIGNOR TO JAMES H. BOYE MANUFACTURING COMPANY, OF CHICAGO, ILLINOIS, A CORPORATION OF ILLINOIS

CURTAIN-ROD-SUPPORTING BRACKET

Application filed December 26, 1929. Serial No. 416,353.

This invention relates to the art of curtain fixtures, and has reference more particularly to an improved adjustable bracket for supporting the end or ends of one or more rods.

5 With a view to enhancing the artistic appearance of the curtain fixture, my improved bracket includes as an element thereof, a member serving primarily as an ornament disposed in a vertical plane crosswise of the 10 curtain rod and extending some distance below the latter and preferably taking the form, in side elevation, of a scroll; which member may serve also the mechanical function of a strut or brace where the main bracket 15 arm (which is preferably adjustable lengthwise) is too light to in itself adequately support the curtain or curtain and shade; the depending ornament, in that case, being apertured at or near its lower end to receive 20 a fastening screw.

One object of the present invention is to provide improved means for attaching the vertical ornament by a swivel joint to the bracket arm so that the lower end of the 25 ornament may be made to lie in contact with the outer face of the top member of the window frame in various adjusted positions of the main adjustable bracket arm, and also in situations where the lower end of the 30 vertical ornament may register with a molding on the frame member.

Another object of the invention is to provide an improved lengthwise adjustable bracket arm, in association with a shade 35 roller support mounted thereon, with means for attaching the shade roller support to the arm that will readily permit lengthwise adjustment of the arm without disturbing the position of the shade roller support relatively 40 to the window frame.

Modern ornamental curtain rods are now quite extensively equipped with detachable end ornaments extending generally lengthwise of the rod, and a still further object of the invention is to provide an improved fastening for such an end ornament permitting 45 the latter to be readily applied and removed by simple push and pull operations.

Still other objects and attendant advantages of the invention will be apparent to per-

sons skilled in the art as the same becomes better understood by reference to the following detailed description taken in connection with the accompanying drawings wherein I have illustrated one practical and 55 approved embodiment of the invention, and in which—

Fig. 1 is a front elevation.

Fig. 2 is a vertical section on the line 2—2 of Fig. 1.

Fig. 3 is a rear elevation in cross section through the bracket arm on the line 3—3 of Fig. 4.

Fig. 4 is a plan section taken on the line 4—4 of Fig. 2.

Fig. 5 is a plan section through the bracket arm and swiveled joint of the vertical ornament, taken on the line 5—5 of Fig. 2, and omitting the shade roller support.

Fig. 6 is an inner side elevation of the telescopic bracket arm, partly in vertical section on the line 6—6 of Fig. 5.

Figs. 7 and 8 are detailed sectional views taken on the lines 7—7 and 8—8, respectively, of Fig. 3.

Fig. 9 is a perspective elevation of the shade roller support.

Fig. 10 is a sectional view illustrating a modification of the swivel joint of the vertical ornament where no end ornament is employed.

Fig. 11 is a detail side elevation of the upper portion of the vertical ornament and its shank.

Referring to the drawings, A may designate a portion of the top horizontal member of a window frame, on which the curtain rod supporting bracket is mounted. I have herein shown the front face of this frame member A as formed with a protuberant molding 85 A', in order to illustrate the adaptability of this device to a window frame member of this type; but it is to be understood that the device is equally applicable to window frames that are plain or have a different molding 90 effect.

The bracket arm itself is formed in two inter-fitting telescoping channel-shaped sections. The inner section 10 is formed with integral vertical end flanges 11 apertured to 105

receive fasteningscrews 12. The outer bracket arm section is an L-shaped member comprising an arm 13 telescoping over the bracket section 10, and an arm 14 extending parallel with the window frame member A and, in the instance shown, of C-shape in cross section, and telescopically receiving one end of the curtain rod 15. I have herein shown the upper and lower lips or flanges of the arm 14 formed with notches 14' to accommodate pull cords to adapt the device to fixtures of the pull-cord type, but this feature is immaterial to the present invention.

The perpendicular wall of the bracket arm 13 is formed with a longitudinal slot 16 which may conveniently have a substantially central enlargement 16' to permit the passage of a screw head for convenience in assembling and separating the two sections of the bracket arm, but this feature is not at all essential. The perpendicular wall of the inner bracket arm 10 is formed with a tapped hole 17' to receive a clamping screw 17 by which the two sections of the arm are rigidly secured together; and for purposes of adjustability of the shade roller support, hereinafter referred to, the bracket arm 10 may have a plurality of longitudinally spaced holes 17', as clearly shown in Figs. 5 and 6, all of these holes registering with the slot 16. The perpendicular wall of the outer bracket arm 13 is formed near its outer end, with a centrally apertured, outwardly pressed centering boss 18, best shown in Fig. 5. 19 designates a vertically disposed and preferably scroll-shaped strip, serving either as an ornament or an ornamental brace, that, as clearly shown in Figs. 1 and 2, lies crosswise of and extends both above and below the bracket arm 14. To the rear face of this ornament is attached, as by soldering or otherwise, a rearwardly extending shank member 20, the inner free end of which is formed with a centrally apertured centering boss 21 within which the centering boss 18 of the bracket arm 13 nests.

Attached to the outer side of the bracket arm 13 is a support or holder for an end ornament. This support preferably comprises a short tube section 22 of C-shape in cross section (Fig. 7) on the inner end of which is a transversely disposed channel-shaped shank member 23, the upper and lower lips 23' of which straddle the top and bottom limbs of the arm 13 as clearly shown in Figs. 2 and 3. This shank member 23 is formed with a centrally apertured centering boss 24 (Fig. 5), within which the centering boss 21 of the ornament shank 20 inter-nests. A clamp screw 25 extends through the apertures of the centering bosses 18 and 21 and screws into the tapped aperture of the centering boss 24, thus securely uniting the several parts on which the centering bosses are formed. The ornament support 22 telescopically receives the stem or shank 26 of the

end ornament 27, as clearly shown in Fig. 3, and to secure the ornament yieldably in place, the support 22 is formed with an integral transversely extending spring tongue 27 that, as the shank of the ornament is pushed inwardly, over rides the rear face of said shank and snaps into a shallow transverse groove 28 in the latter, as shown in Figs. 3 and 8, thus yieldably locking the end ornament to its seat in the support or holder 22.

The device as thus far described is complete for a fixture designed to support only a curtain or drape. In order to adapt the structure to also carry a shade roller, I preferably equip the same with a shade roller support that is mounted on and carried by the arm 13 of the telescopic bracket. This shade roller support, shown in isolated detail in Fig. 9, may be bent to shape from a single sheet metal blank, and consists substantially of an inverted U-shaped member that is hung over the arm 13 and is formed on its inner side with a generally rectangular socket to receive the end bearing member of a shade roller. More specifically, the shade roller support has a top horizontal limb 29, a depending outer vertical limb 30 that is formed with a central vertical slot 31 to straddle the neck of the clamp screw 18, and an inner depending seat or chair 32 adapted to receive the end bearing member of a shade roller 33. Manifestly, since this shade roller support is secured to the bracket arm 10 by the clamp screw 17, its position relatively to the window frame is determined by the position of the clamp screw in any one of the holes 17' of the bracket arm 10. However, by simply loosening the clamp screw 17, the arm 13 may be drawn outwardly or pushed inwardly, thus adjusting the position of the curtain rod 15 toward and from the window frame as desired.

Now, it will be observed that when the last described adjustment is made, the pivot joint of the vertical ornament 19 is also bodily shifted in horizontal direction; but, since the shank member 20 of the ornament is free to turn or swivel on its pivot screw 25, the lower end of the ornament can readily be adjusted into contact with the window frame member, or a molding thereon, by a simple swinging movement, making it unnecessary to detach and re-assemble the vertical ornament when the bracket arm is thus adjusted. Furthermore, the described construction enables the ornament 19 to be properly fitted to window frames of different thicknesses or molded forms without any adjustment of the bracket arm, since the latter having been attached to the frame, the ornament 19 can then be swung into contact with the window frame.

In Fig. 2 I have shown the lower end portion of the ornament 19 apertured to re-

ceive a screw 34 by which the lower end of the ornament may be positively secured to the window frame so as to serve not only as an ornament, but also as a brace, partially relieving the strain on the main bracket arm.

5 The ornament will preferably be used in this capacity where the fixture has to support heavy curtains or drapes, or the stock of the main bracket arm is too light to rigidly support the curtains or curtains and shades.

10 So far as the capacity for adjustment of the ornament 19 to varying lengths of bracket arms and varying shapes of window frame is concerned, the formation of the swivel 15 joint by inter-nested centering bosses is manifestly not essential; but the described construction is preferable because greatly facilitating the application of the pivot screw 25, and affording a better friction joint.

20 Furthermore, where the end ornament and its support or keeper may not be used, the described adjustability of the vertical ornament 19 may be effected by simply entering the pivot screw 25 into a tapped aperture 25 in the shank 20, as illustrated in Fig. 10.

30 I have herein shown and described one practical embodiment of the invention which satisfactorily effectuates the stated purposes and objects thereof, but I do not limit the invention to the specific details shown for purpose of illustration, except to the extent clearly indicated in specific claims.

I claim:

1. The combination with a curtain rod 35 supporting bracket adapted for attachment to a window frame, of a strip disposed cross-wise of the curtain rod and depending below the latter, said strip being frictionally swiveled on said bracket whereby the depending portion of said strip may be adjusted by a 40 swinging movement into contact with the window frame.

2. The combination with a curtain rod supporting bracket comprising an inner arm 45 adapted for attachment to a window frame and an outer arm slidable on and length-wise of said inner arm, of means for clamping said outer arm in adjusted position on said inner arm, and a strip disposed cross-wise of said curtain rod and depending below the latter, said strip being frictionally swiveled on said outer bracket arm to swing in a vertical plane, whereby the depending portion of said strip may be adjusted by a 50 swinging movement into contact with the window frame in any adjusted position of said outer arm.

55 3. The combination with a curtain rod supporting bracket adapted for attachment to a window frame, of a strip disposed in a vertical plane in front of said bracket and depending below the latter, said strip having a rearwardly extending shank frictionally swiveled on one side of said bracket, 60 whereby the depending portion of said strip

may be adjusted by a swinging movement into contact with the window frame.

4. The combination with a curtain rod supporting bracket, comprising an inner arm adapted for attachment to a window frame 70 and an outer arm telescopically engaged with said inner arm, of means for clamping said outer arm in adjusted position on said inner arm, and a strip disposed in a vertical plane in front of said bracket and depending below the latter, said strip having a rearwardly extending shank frictionally swiveled on one side of said outer arm, whereby the depending portion of said strip may be adjusted by a swinging movement into contact with the window frame. 75

5. The combination with a curtain rod supporting bracket adapted for attachment to a window frame and formed with an aperture in a side wall thereof, of a strip disposed in a vertical plane in front of said bracket and depending below the latter, said strip having a rearwardly extending shank formed with an aperture registering with the aperture of said bracket, a plate overlying 80 the apertured portion of said shank and formed with a tapped hole, and a screw extending freely through the apertures of said bracket and shank and engaged with the tapped hole of said plate, said screw serving as a clamp for said apertured parts and as a pivot for said strip. 85

6. The combination with a curtain rod supporting bracket, comprising an inner arm adapted for attachment to a window frame 100 and an outer arm telescopically engaged with said inner arm and formed with an apertured centering boss in a side wall thereof, of means for clamping said outer arm in adjusted position on said inner arm, a strip disposed in a vertical plane in front of said bracket and depending below the latter, said strip having a rearwardly extending shank formed with an apertured centering boss registering with the centering boss of said outer arm, a plate formed with a centering boss registering with the centering boss of said shank and having a tapped hole, and a screw extending freely through the apertures of the centering bosses of said bracket arm and shank and engaged with the tapped hole of the centering boss of said plate, said screw serving as a clamp for said apertured parts and as a pivot for said strip. 105 110 115

7. The combination with a curtain rod supporting bracket adapted for attachment to a window frame, of a brace disposed cross-wise of the curtain rod and depending below the latter, said brace being swiveled on said bracket whereby the depending portion of said brace may be adjusted by a swinging movement into contact with the window frame, and means for attaching the lower portion of said brace to the window frame. 120 125

8. The combination with a curtain rod 130

supporting bracket comprising an inner arm adapted for attachment to a window frame and an outer arm slidable on and lengthwise of said inner arm, of means for clamping said outer arm in adjusted position on said inner arm, and a brace disposed in a vertical plane in front of said bracket and depending below the latter, said brace having a rearwardly extending shank frictionally swiveled on one side of said bracket, whereby the depending portion of said brace may be adjusted by a swinging movement into contact with the window frame, and means for attaching the lower portion of said brace to the window frame.
